DESIGN FOR A CONTAINER CAP

Albert H. Jung, Flushing, N. Y., assignor to Victor Metal Products Corporation, Brooklyn, N. Y., a corporation of New York

Application November 25, 1939, Serial No. 88,477

Term of patent 7 years

To all whom it may concern:

Be it known that I, Albert H. Jung, a citizen of the United States and resident of Flushing, Long Island, in the Borough of Queens, county of Queens, city and State of New York, have invented a new, original, and ornamental Design for a Container Cap, of which the following is a specification, reference being had to the accompanying drawing, forming part thereof.

Fig. 1 is a top plan view of a container cap showing my new design.

Fig. 2 is a front elevation of the same.

Fig. 3 is a horizontal section taken on the line 3—3 of Fig. 2 and showing the concave fluting.

The characteristic features of the design reside in a cap of the contour shown provided with concaved fluting arranged thereon as illustrated and which is widest at its base and tapers uniformly towards the apex of the cap thereby leaving well defined narrower surface portions of uniform width radiating out from the apex of the cap and presenting the appearance of spokes in the end view of the cap.

I claim:

The ornamental design for a container cap, substantially as shown and described.

ALBERT H. JUNG.
